ATTORNEY

UNITED STATES PATENT OFFICE.

BYRON PHELPS, OF SEATTLE, WASHINGTON, ASSIGNOR OF ONE-HALF TO
THEODORE NELSON, OF CHICAGO, ILLINOIS.

LOCK.

SPECIFICATION forming part of Letters Patent No. 631,432, dated August 22, 1899.

Application filed January 21, 1899. Serial No. 702,910. (No model.)

To all whom it may concern

Be it known that I, BYRON PHELPS, a citizen of the United States, residing at Seattle, county of King, State of Washington, have 55 invented certain new and useful Improvements in Locks, of which the following is a full, clear, and exact description.

My invention relates to locks; and my object is to improve the construction of the same 10 and particularly with reference to a frame for a lock adapted to be inserted in a notch in the stile of a door, such as shown in my Patents Nos. 626,340 and 626,341, dated June 6, 1899.

15 In the preferred embodiment of my invention shown in the drawings, Figure 1 represents a plan view, and Fig. 2 a front elevation, of my improved lock-frame.

In the embodiment shown in the drawings, 20 A represents the main portion of the frame, which has spindle-bearings B and C, which may be merely orifices in the sides, but which in this embodiment extend laterally from the sides D and E.

25 F is a face-plate, preferably extending from one side of the frame across the other side and projecting therefrom, as shown at f. This face-plate also has a bolt-aperture f'. This general form of lock is claimed by me in my

30 Patent No. 626,340, dated June 6, 1899, in which patent is shown one embodiment of the operative parts or features that coöperate with each other and with the frame when the same is properly applied to a door and which

35 shows the manner of applying the frame to the stile of a door. This frame is adapted to be inserted in a notch in the stile of a door, and in my former application the frame was more particularly intended to be fastened in

40 place in the stile by screws through the escutcheon-plates. It is, however, often desirable that the front part of the frame shall be supported directly by the door in order to more securely fix it and preserve its alignment in the notch, and for this purpose I have

45 provided lugs G G, preferably integral with the face-plate and extending therefrom substantially perpendicularly to the face-plate and also to the axis of the bearings represented by the line X X, Fig. 2. The front face of these lugs is preferably in the same

plane with that of the face-plate, and said lugs are preferably so narrow that the face-plate extends laterally at each side of the same, so that said lugs will not extend clear 55 across the stile of the door. Countersunk screw-holes g g are provided in these lugs, so that the same may be screwed to the stile of the door. The face-plate and lugs preferably, as shown in Fig. 1, stand at an angle 60 with the sides of the frame.

It will be obvious that many changes may be made in the construction herein disclosed without departing from the spirit of my invention.

What I claim is—

1. In a lock a main frame to support the latch mechanism and adapted to be inserted in a notch in the stile of a door, having sides, spindle-bearings in said sides, a face-plate 70 and a lug extending from said face-plate substantially perpendicularly to the face-plate and axis of the spindle-bearings and narrower than the said face-plate so as to leave said face-plate projecting from one side of said 75 lug, said lug having a hole therethrough with a countersunk portion on its front face.

2. In a lock a main frame to support the latch mechanism and adapted to be inserted in a notch in the stile of a door, having a plurality of separated and hollow spindle-bearings attached thereto and extending transversely outside of the same and a face-plate, 80 said face-plate having a bolt-aperture and projecting laterally of said frame, said face-plate also having a plurality of lugs extending laterally of said face-plate substantially perpendicularly to the same and also to the axis of said spindle-bearings, the front faces of which lugs are in substantially the same 85 plane with the front face of said side plate, said lugs being narrower than said face-plate so as to allow said face-plate to project at each side of said lugs, said lugs having holes therein and said holes being countersunk on the 90 front faces of said lugs.

Signed at New Britain, Connecticut, this 19th day of January, 1899.

BYRON PHELPS.
